United States Patent Office

Des. 226,632
Patented Apr. 3, 1973

226,632

COMBINED CASH REGISTER AND DATA TERMINAL

Randall D. Jackson, Cincinnati, Ohio, assignor to Comp-
Acct, Inc., Cincinnati, Ohio

Filed Apr. 29, 1971, Ser. No. 138,853

Term of patent 14 years

Int. Cl. D20—99

U.S. Cl. D52—4 A

FIG. 2

FIG. 4

Fig. 2

Fig. 6

FIG. 1 is a perspective view of the front and right side of a combined cash register and data terminal showing my new design;

FIG. 2 is a perspective view of the front and left side thereof;

FIG. 3 is a top plan view thereof;

FIG. 4 is another top plan view thereof as it appears with the cash box in open position;

FIG. 5 is a rear view thereof on reduced scale;

FIG. 6 is a bottom view thereof;

FIG. 7 is a perspective view of the front, left side and top of the removable cash box;

FIG. 8 is a right side view of the cash box, the left side being a mirror image thereof;

FIG. 9 is a rear view of the cash box; and

FIG. 10 is a bottom plan view thereof.

I claim:

The ornamental design for a combined cash register and data terminal, substantially as shown.
